UNITED STATES PATENT OFFICE.

MOSES H. MASON, OF ATTLEBOROUGH, MASSACHUSETTS, ASSIGNOR TO
MASON, DRAPER & CO., OF SAME PLACE.

IMPROVEMENT IN BRACELETS.

Specification forming part of Letters Patent No. 125,402, dated April 9, 1872.

I, MOSES H. MASON, of Attleborough, in the county of Bristol and State of Massachusetts, have invented an Improvement in the Manufacture of Bracelets, of which the following is a specification:

The nature of my invention consists in producing a cheap substitute for the back piece, usually soldered upon the inside of an ordinary hinged bracelet.

Figure 1 represents an edge view, and Fig. 2 a sectional side view of the ordinary hinged bracelet. Figs. 3, 4, 5, 6, and 7 represent sectional views of my improvement in its several modifications.

It has been the common practice heretofore to fasten upon the inner side of the ordinary hinged bracelet a strip of metal, A, in order to render the bracelet agreeable to the wrist of the wearer and to present the appearance of solidity. The expense of preparing and soldering this piece in place is quite a considerable item in the cost of manufacture. I avoid this, and at the same time produce an article having the same appearance when on the wrist, and also properly agreeable to the wearer, by turning the edges of the plain strip of stock of which the bracelet is to be made so as to form a round, square, or grooved edge, the edges of the strip of stock extending beyond to form the inner bearing of the bracelet, either straightly or on a flattened curve, as shown in the several sectional drawings, Figs. 3, 4, 5, 6, and 7, where *a a* are the edges of the bracelet, and *b b* the straight or flattened curved portions referred to. In Fig. 3 the stock is formed up so as to produce a semi-circular edge, *a*, with a slightly curved inner portion, *b*, extending to near the center of the bracelet to meet a similar curved portion ex-

tending from the other side. This forms a cheap and readily-made substitute for the soldered piece A, since the face of the bracelet, the edges, and bearing for the wrist are drawn out of a continuous strip of stock. Fig. 4 shows a squarely-formed edge, with the bearing-flanges *b b* made straight and extending from each edge a sufficient distance toward the middle of the bracelet to give comfort to the wearer. Figs. 5 and 6 are other modifications illustrating the same principles, the bearing-flanges *b b* being slightly curved. Fig. 7 shows the square-edged bracelet with a square wire inserted, so as to stiffen the same; and in this case I continue beyond the straight or slightly-curved portion *b b* and turn the flange *c*, which serves to secure the wire without the use of solder, and completely hides the baser metal of the wire.

I am aware that Frederick Wessel, in his design patent No. 4,256, dated July 19, 1870, has claimed the invention of a similar bracelet having a roll upon its edge, which will give only a narrow cylindrical bearing upon the wrist of the wearer; therefore I make no claim to a bracelet having an edge furnished with a roll; but

What I claim as my invention is—

The inner bearing or lips *b b* turned from both edges, *a a*, of a bracelet, and which affect the wrist of the wearer, either straight or on a flattened curve, and made to differ from the curve of the edges *a a*, being also drawn from the same strip of stock, substantially as described.

MOSES H. MASON.
